NEEDLE GUARD FOR SEWING MACHINES

Filed Oct. 8, 1928

Attn: Mr. C. F. Munn

UNITED STATES PATENT OFFICE

AUGUSTUS LAVOIE, OF LEOMINSTER, MASSACHUSETTS

NEEDLE GUARD FOR SEWING MACHINES

Application filed October 8, 1928. Serial No. 311,051.

This invention relates to power sewing machines and particularly to machines for sewing buttons on fabric or other material. Such machines are commonly operated by mechanical or electric power, and the needle is driven with such force that serious injury may be caused if the operator's thumb or fingers is pierced by the needle.

It is the object of my invention to provide a needle guard for such machines so constructed that the operator is effectively protected while the machine is stitching.

A further object is to provide means by which the guard will be removed from operative position when the machine is stopped and the holder is raised to release the attached button and to receive a new button in place thereof.

My invention further relates to arrangements and combinations of parts which will be hereinafter described and more particularly pointed out in the appended claims.

A preferred form of the invention is shown in the drawings in which

Fig. 1 is a plan view of portions of a sewing machine having my improved guard mounted thereon;

Fig. 2 is a front elevation of the parts shown in Fig. 1;

Fig. 3 is a partial front elevation, similar to Fig. 2, but showing the parts in a different position;

Fig. 4 is a sectional front elevation, taken along the line 4—4 in Fig. 1; and

Fig. 5 is a detail side elevation, looking in the direction of the arrow 5 in Fig. 1.

Referring to the drawings, I have shown my improved needle guard mounted on a sewing machine having a top surface or table 10 on which a fabric F is supported in position to receive buttons B to be stitched thereon.

Each button B is positioned by a button holder 15 forming the front end portion of an arm 16 mounted on a fixed pivot and movable upward by a link 17 (Fig. 5) connected to actuating mechanism (not shown). A spring 18 normally retains the button holder 15 in lowered or button-holding position, and the holder is raised by the operator after

each button is attached, to permit the displacement thereof and the insertion of a new button in the holder.

A needle 20 (Fig. 2) is mounted in the usual reciprocating needle bar 21 and reciprocates vertically during the stitching operation. The parts thus far described are of the usual construction and in themselves form no part of my present invention.

My improved needle guard comprises a stand 30 (Figs. 1 and 2) adjustably secured to the table 10 by a clamping screw 31. A needle guard 32 is pivoted on a stud 33 fixed in the stand 30.

The guard 32 is made in two pieces, as clearly shown in Fig. 1, these two pieces having a slotted connection and being secured together by clamping screws 34. By loosening the screws 34, the guard may be adjusted forward or rearward as desired. The outer end of the guard is curved in plan section, as indicated in Fig. 1, to partially surround the needle 20 and button B.

A flange or ledge 36 projects rearward from the upper edge of the guard 32, this flange protecting the operator from flying fragments of broken needles. A stop screw 38 (Fig. 2) is adjustably clamped to the stand 30 and limits downward swinging movement of the guard 32.

An actuating lever 40 is also pivoted on the stud 33 previously described, said lever being made in two parts as indicated in Fig. 4, which parts are relatively adjustable vertically and which may be secured together by clamping screws 41. The outer end of the lever 40 overlies the button holder arm 16, as indicated in Fig. 5. A tension spring 42 acts to draw the lever 40 yieldingly downward.

At its left hand end, the lever 40 is provided with a stud 44 (Fig. 1) extending freely through a slot 45 (Fig. 2) in the left hand end of an intermediate lever 50. The lever 50 is pivoted at 51 on an extension 52 of the stand 30 and the right hand end of the lever 50 is connected by a link 54 to a stud 55 in the needle guard 32.

The spring 42 acts through the lever 40, the intermediate lever 50, and the link 54 to

hold the needle guard 32 firmly against the stop screw 38, with all parts under spring tension. The operative position of the guard may be shifted upward or downward by adjustment of the stop screw 38.

6 While I have shown a spring 18 for depressing the button holder, this spring may at times be omitted, as the spring 42 may be relied on to move the button holder as well as the needle guard to lowered or operative position.

10 Having described the details of construction of my improved guard, the use and advantages thereof will be readily apparent. 15 The normal position of the parts is as indicated in Figs. 1 and 2, with the guard 32 in lowered position and in front of the needle 20, effectively preventing injury to the operator.

20 After a button has been attached, the operator raises the button holder 15 and arm 16, commonly by the use of a foot pedal. As the arm 16 is moved upward, it engages the lever 40, moving the same in the direction of the arrow *a* in Fig. 2. Such movement depresses the stud 44, as indicated by the arrow *b* in Fig. 4, swinging the intermediate lever 50 on its pivot 51 and moving the end of the link 54 upward, as indicated by the 25 arrow *c* in Fig. 2. This causes the guard 32 to be swung about its pivot 33 in the direction of the arrow *d* in Fig. 2, the parts being moved from the position shown in Fig. 2 to that shown in Fig. 3. In the latter position, 30 the guard 32 is substantially raised and does not interfere with the insertion of a new button in the holder 15. As the button holder is allowed to descend on the fabric *F*, the guard automatically resumes its operative position.

40 The needle guard is thus automatically removed from operative position by the raising of the button holder and is automatically restored by the return of the button holder to lowered or operative position. All parts 45 of my improved needle guard are of simple but substantial construction and are easily manufactured by punch or press operations. My invention has been found reliable and extremely effective when in use.

50 Having thus described my invention and the advantages thereof, I do not wish to be limited to the details herein disclosed, otherwise than as set forth in the claims, but what I claim is:—

55 1. In a sewing machine, a button holder movable toward and from button-holding position, and a needle guard movable relative to said button holder by said button holder toward and from operative position.

60 2. In a sewing machine, a button holder movable toward and from button-holding position, a needle guard, yielding means to move said guard to operative position, and connections between said button holder and said 65 needle guard by which said guard is posi-

tively moved relative to said button holder and from operative position when said button holder is moved from holding position.

3. In a sewing machine, a button holder movable toward and from button-holding position, a needle guard, yielding means to move said guard to operative position, and connections between said button holder and said needle guard by which said guard is positively moved from operative position when 70 said button holder is moved from holding position, the movement of said guard being many times greater than the movement of said holder.

4. In a sewing machine, a button holder movable toward and from button-holding position, a needle guard, yielding means to move said guard to operative position, and multiplying connections between said holder and guard by which said guard is positively moved from operative position when 80 said holder is moved from holding position, the movement of said guard being at greatly increased speed.

5. In a sewing machine, a button holder movable toward and from button-holding position, a needle guard mounted to swing about a fixed pivot, and a lever mounted on a fixed pivot and having operating connections to said guard, a portion of said lever being directly engaged and moved by said button holder as said holder is moved away from operative position.

6. The combination in a sewing machine as set forth in claim 5, in which the lever is made in two parts relatively adjustable to determine the extent of movement of the needle guard.

7. The combination in a sewing machine as set forth in claim 5, in which said operating connections include an intermediate pivoted lever having a stud and slot connection to said first named lever and having a link connection to said needle guard.

8. The combination in a sewing machine as set forth in claim 5, in which an adjustable abutment is provided to limit downward movement of said guard.

9. In a sewing machine, a button holder movable toward and from button-holding position, and a needle guard movable relative to said button holder by said button holder toward and from operative position, said guard having a substantially vertical protecting portion and having a rearwardly extending flange at its upper edge to intercept fragments of broken needles.

10. In a sewing machine, a button holder movable toward and from button-holding position, a needle guard, yielding means to move said guard to operative position, and a single means by which said guard is positively moved from operative position when said button holder is moved from holding position, the movement of said guard being related

tively large and the movement of said holder relatively small.

11. In a sewing machine, a button holder movable toward and from button-holding position, yielding means to move said holder to operative position, a needle guard, yielding means to move said guard to operative position, and means connected to move said guard positively from operative position and to move said button holder positively from holding position, and to cause a movement of said guard relative to said button holder and of greatly increased extent.

12. In testimony whereof I have hereunto affixed my signature.

AUGUSTUS LAVOIE.
